(57) **CLAIM**

We claim the ornamental design for a kettle, as shown and described.

DESCRIPTION

FIG. 1 is a front perspective view of a kettle, showing our new design;

FIG. 2 is a rear perspective view of the kettle of FIG. 1; FIG. 3 is a front elevational view of the kettle of FIG. 1; FIG. 4 is a rear elevational view of the kettle of FIG. 1; FIG. 5 is a first side elevational view of the kettle of FIG. 1; FIG. 6 is a second side elevational view of the kettle of FIG. 1;

FIG. 7 is a top plan view of the kettle of FIG. 1; and, FIG. 8 is a bottom plan view of the kettle of FIG. 1. The broken lines in the drawing views represent environmental structure of a kettle, and form no part of the claimed design.
